UNITED STATES PATENT OFFICE.

CLIFTON K. RAINY, OF BIRMINGHAM, ALABAMA.

TYPE-WRITER ESCAPEMENT MECHANISM.

1,104,003.

Specification of Letters Patent. Patented July 21, 1914.

Application filed October 19, 1912. Serial No. 726,838.

To all whom it may concern:

Be it known that I, CLIFTON K. RAINY, a citizen of the United States, residing at Birmingham, in the county of Jefferson and State of Alabama, have invented certain new and useful Improvements in Type-Writer Escapement Mechanism; and I do hereby declare the following to be a full, clear, and exact description of the invention, such as will enable others skilled in the art to which it appertains to make and use the same.

My invention relates to a carriage escapement mechanism for typewriting, tabulating and other forms of recording machines.

The primary object of my invention is to provide an improved escapement which permits a swift and uninterrupted movement of the carriage incident to the successive formation of the letters or characters.

Another object is to provide an escapement mechanism of such construction as to positively stop the carriage at the completion of one letter space, thus obviating the possibility of the carriage moving more than one space during the single operation of a key lever.

Briefly stated, my invention consists in providing coöperating means for the escapement wheel which shall continuously travel across the path of said wheel, and successively engage therewith in contradistinction to the pair of reciprocating dogs commonly employed for permitting an intermittent movement of said wheel.

Up to the present time, so far as I am aware, the desired movement of the carriage has been attained by means of the ordinary escapement wheel and rock arm carrying one or two dogs fixed or pivoted, which reciprocate across the path of the escapement wheel and alternately stop and release the same and consequently the carriage connected therewith. In these forms of escapement, the shock incident to the stopping of the carriage at each letter space is delivered upon either a single dog or one of a pair, and such excessive use of these parts causes them to be quickly worn and their action inaccurate because of the disturbing of their delicate adjustment.

My invention contemplates a broad departure from the old rocker motion where-in is employed a rotary element carrying a plurality of spring actuated dogs adapted to be partially rotated upon the operation of

a key to permit the escape of one tooth of the escapement wheel.

Any number of spring actuated dogs may be employed upon my rotary stop and release, and thus the life of this portion of the machine is proportionately increased.

On the drawings, Figure 1 is a vertical sectional view, showing a portion of the top of the frame of a typewriter, the rear face of the escapement wheel having my improved spacing wheel applied thereto. Figs. 2 and 3 are fragmentary rear views, the first showing one tooth of the escapement wheel engaged against a pivoted dog, and the second showing the position of the pivoted dog during the reverse movement of the escapement wheel. Fig. 4 is a side elevation of my improved spacing wheel taken on the line 4—4 of Fig. 1. Fig. 5 is a fragmentary view of the opposite side of the spacing wheel to that shown in Fig. 4. Fig. 6 is a detail perspective view of one of the pivoted dogs.

Referring to the drawings, 1 represents the top plate of the stationary frame of a typewriter and 2 the shaft, carrying the usual escapement wheel 3. The escapement wheel is controlled by the spacing wheel 4, which may be conveniently placed upon the rocker shaft 5 now generally employed upon Remington and other typewriting machines, for supporting the old form of rocking dog. The spacing wheel 4 is preferably located beneath the escapement wheel 3 and is provided with a plurality of radially projecting spring actuated dogs 6, adapted to successively disengage and release one tooth of the escapement wheel 3 upon each operation of the key lever (not shown). Anchoring plates 7 are secured to one face of the wheel 4 by screws 8, the outer ends of the anchoring plates being bifurcated to receive the tongue extension 9 of the dogs 6. The adjacent ends of the plates 7 and dogs 6 are connected by a pivot pin 10, inwardly of the peripheral edge of the wheel 4, so that the portion of said wheel projecting beyond the pivotal point provides a stop flange 11 for limiting the movement of the dogs. The dogs 6 project outwardly from the wheel 4 a distance substantially equal to the length of the teeth of the escapement wheel 3 and are normally retained inclined toward the advancing tooth of the escapement wheel by means of a spider spring, having the central portion 12 thereof secured against the

face of the wheel 4 by screws 13 and the radially projecting arms 14 normally lying against the flat surface 15 of the pivoted end of the dog.

5 As clearly illustrated in Figs. 1 and 2, the movement of a tooth of the escapement wheel against a dog of the spacing wheel 4 causes the tension of the spring arm 14 to be overcome and the dog to be engaged 10 against the projecting flange 11 of the wheel 4. It will be further seen that the normal inclination of the dogs 6 leaves sufficient space between the depressed dog and the adjacent one for a tooth of the escapement 15 wheel to pass therebetween when the spacing wheel 4 is rotated a portion of a revolution.

The usual connecting rod 15 is employed that connects the universal bar (not shown), 20 with the escapement mechanism, and in this instance it is connected with a pitman 16 having a slot 17 therein working over the shaft 5. The pitman 16 is located upon the side of the spacing wheel 4 opposite that 25 face to which the dogs 6 are pivoted, and to this face of the wheel is secured an annular rack 18 with which is adapted to coöperate the rigid dog 19, formed laterally upon the pitman 16, said pitman being normally retained in raised position by means of a compression spring 20. A depression of the connecting rod 15 will cause the rigid dog 19 to engage one tooth of the annular rack 18 and partially rotate the spacing wheel 4, and in 30 order to prevent further rotation of said member 4, I provide a wedge shaped lug 21 at the upper end of the pitman 16 which enters between two teeth at the upper portion of the annular rack 18 at the end of the 40 down stroke of the pitman. During the return stroke of the pitman, rotation of the wheel 4 is prevented by means of a spring dog 22. In order that the pitman 16 will readily ride over the teeth of the annular 45 rack 18 upon the up stroke, a spring 23 is positioned over the shaft 5 and has its opposite ends bearing against said pitman 16 and an adjustable collar 24 mounted over said shaft.

50 The teeth of the annular rack 18 are of such size and so arranged as to cause one pivoted dog 6 to pass by and release one tooth of the escapement wheel 3 upon one operation of a key of a typewriter. While 55 I have herein shown the pitman 16 connected with an inclined connecting rod 15, it will be clearly understood that said rod

and pitman may be shifted to either a horizontal or vertical position without materially changing the construction of my invention.

What I claim is:—

1. In combination, a shaft, a spacing wheel thereon, an annular rack secured to one side of said wheel, a longitudinally slideable member mounted on said shaft, a laterally projecting tooth carried by said member engaging said rack; and a wedge shape lug carried by said member adapted to engage between the teeth of said rack during the operation of said member. 65

2. In combination, a shaft, a wheel on said shaft, an annular rack projecting laterally from said wheel, a member mounted on said shaft and having longitudinal and transverse movement thereon, a tooth carried by said member engaging said rack, and means tending to move said tooth transversely against said rack. 75

3. In combination, a shaft, a spacing wheel thereon, an annular rack projecting laterally from said wheel, a member mounted on said shaft and movable longitudinally and transversely thereon, and means on said member adapted to engage said rack to rotate said wheel. 80

4. In combination, a shaft, a wheel on said shaft, an annular rack projecting laterally from said wheel, a member mounted on said shaft having longitudinal and transverse movement thereon and adapted to coöperate with said rack to intermittently rotate said wheel, and means on said member adapted to lock said rack against rotation subsequently to an operation of said member. 90

5. In combination, a shaft, a wheel on said shaft, an annular rack projecting laterally from said wheel, a member mounted on said shaft having longitudinal and transverse movement thereon and adapted to coöperate with said rack to intermittently rotate said wheel, means tending to move said member transversely against said rack, and means on said member adapted to lock said rack against rotation subsequently to an operation of said member. 100

In testimony whereof I have signed my name to this specification in the presence of two subscribing witnesses.

CLIFTON K. RAINY.
